DESIGN FOR A WEDDING RING

Nathan A. Cohn, Los Angeles, Calif.

Original application April 12, 1939, Serial No. 84,231. Divided and this application August 7, 1939, Serial No. 86,529

Term of patent 3½ years

To all whom it may concern:

Be it known that I, Nathan A. Cohn, a citizen of the United States, residing at Los Angeles, in the county of Los Angeles and State of California, have invented a new, original, and ornamental Design for a Wedding Ring, of which the following is a specification, reference being had to the accompanying drawing, forming part thereof.

This application has been divided out of my original application having the title Bridal pair engagement and wedding rings, Ser. No. D-84,231, filed April 12, 1939.

The figure is a perspective view of a wedding ring, showing my new design.

I claim:

The ornamental design for a wedding ring, as shown.

NATHAN A. COHN.
